SWITCH-THAWING DEVICE.

1,198,034.

Specification of Letters Patent.

Patented Sept. 12, 1916.

Application filed March 15, 1915. Serial No. 14,598.

To all whom it may concern:

Be it known that we, FRANK A. HIGGINS and THOMAS M. DUNNING, citizens of the United States of America, residing at New Brunswick, county of Middlesex, and Jersey City, county of Hudson, and State of New Jersey, respectively, have invented new and useful Improvements in Switch-Thawing Devices, of which the following is a specification.

The general object of the invention is to effect in a simple, expeditious and effective manner, the thawing of the movable element of a switch rail of a railway track when, in the winter time, this has become frozen to the surface on which it bears, or has otherwise been rendered inoperative by the presence of ice or snow or both disposed in its path of movement. And to this end the invention resides in arranging in the bed of the railway track and underneath the switch, one or more trays adapted for holding contained a combustible liquid so that when this is ignited the flame thereof, upon mounting upwardly, will envelop the frozen switch and thereby cause the thawing thereof.

Another feature of the invention resides in providing if desired, a receptacle for the combustible liquid, and in adapting and arranging this receptacle to discharge into the tray or trays.

Other objects will appear and be better understood from that embodiment of my invention of which the following is a specification, reference being had to the accompanying drawing forming part hereof, in which:

Figure 1 is a plan of one embodiment of the invention in use. Fig. 2 is an enlarged cross sectional detail of the inner side of the track shown in Fig. 1. Fig. 3 is a contracted fragment partly in section and in side elevation of one end portion of the reservoir or supply.

For purposes of illustration we have shown the invention in use with two movable switch rails. These are indicated in the drawings by *a* and *b*. The stationary rails of the track are indicated by *c* and *d*, the cross ties by *e*, and the links connecting the movable rails *a* and *b* by *f* and *g*. Since the operating mechanism for the switch rails *a* and *b* forms no part of the present invention, it is not deemed necessary to in-

dicate such mechanism here, nor further to describe in detail the parts just indicated since the structure of these parts forms no part of the present invention.

The construction of the reservoir or supply of this invention is based on the principle that the flow of liquid from a liquid-holding container having an outlet opening will always be controlled by the position of that opening with respect to the surface of the liquid in the container. Hence the outlet of the container of the present invention is adjustable to variable distances either above or below the surface of the liquid in the container or reservoir. With this construction it is obvious that when the outlet is above the level of the liquid in the container the liquid may be retained in the container without requiring the use of valves and the like. The reservoir or container is designed for holding an inflammable liquid, such as crude oil, kerosene, and the like. And forming part of the invention is a tray also adapted for holding a quantity of the same kind of liquid as is held by the reservoir or container. The reservoir is positioned with such relation to the tray that the outlet of the reservoir will direct the inflammable liquid into the tray when the said outlet is in one position of adjustment and the tray is disposed with such relation to the adjacent switch rail that the flame of the liquid in the tray when the said liquid is ignited, will either wholly or in part envelop the switch rail.

The reservoir or container shown in Figs. 1 to 3 inclusive and indicated generally by *h*, is formed of metallic tubing, access to the interior of which is had through the ends and the axis of the openings in these ends is at an angle to the axis of the tube so that the filling of the tube through either end may be readily effected when the axes of the end openings extend vertically upward. In the form shown in Figs. 1 and 3 the peculiar disposition of the end openings is had by attaching elbows 5—5 in any suitable manner to the ends of the tube and adapting the outer ends of these elbows to take suitable closures. In Fig. 3 an effective type of closure is shown as consisting of a plug 6 screwed into the elbow 5 and having a central opening through which the inflammable liquid is passed in the act of filling the tube. The said central open-

2
ing being screw threaded to receive a bushing 7 which functions to admit atmospheric pressure to the surface of the liquid in the tube so as to facilitate the discharging thereof when the outlet of the tube is adjusted into discharging position.

5 The outlet of the reservoir shown in Figs. 1 to 3 is a nozzle in the form of a tube of relatively small diameter and indicated by 8. The inner end of this nozzle 8 is directed into a lateral opening of the container and is suitably secured against displacement in the said opening. With this construction it is obvious that the nozzle or outlet 10 extends substantially radially of reservoir or container *h*, consequently when the outer end of the outlet is disposed above the level of the liquid the same will not flow from the container or reservoir.

15 20 The container or reservoir is adjustably secured to its support above the tray and in the present instance such container or reservoir is shown as supported by the cross ties *e* and adjacent to the ends thereof and outwardly of the track rails. This disposition of the container or reservoir precludes any probability of contact with extremely low disposed or displaced parts of the running gear of the cars which travel on the track.

25 30 As shown in the drawings the container or reservoir is disposed horizontally and it is rendered adjustable by mounting it in yokes 9 the ends of the limbs of which are outwardly secured to the cross ties *e*, by screws 10 or their equivalents, it being understood that the presence of the yokes will not prevent the turning of the container or reservoir by applying pressure with a suitable implement, such as a wrench, to any desirable portion thereof. In order to require but a minimum amount of turning movement to adjust the outlet from the position shown by full lines in Fig. 2 of the drawings to that shown by dotted lines and at the same

35 40 time to require for receiving the inner end of the outlet an opening whose axis will be at a radius to the container or reservoir *h*, the inner end portion of the outlet is offset as indicated by 11. And further in order to 45 permit of the use of an outlet of such diameter as will not readily clog and will at the same time impede the flow of liquid through the outlet to the same extent as would be had with an outlet of relatively small diameter, a loop 12 is formed intermediate of the ends of the outlet. This loop by its presence, also functions as a trap to prevent the entrance of dust or dirt into the reservoir or container through the outlet when the same 50 is disposed in the position shown by full lines in Fig. 2.

55 The tray 13 of this invention is shown as adapted for coöperating with the container just described. But it will be obvious, from what will hereinafter appear, that the use of

the tray does not depend on any specific form of container or other means for applying combustible liquid. The tray is by preference formed of metal and is arranged between adjacent cross ties, *e*—*e* and held by any suitable support, such as the road-bed 70 14. The tray is so proportioned in length as to readily extend from a position below the switch rail *b* and stationary rail *d* to a point substantially in alinement with the inner 75 end of the outlet whereby to provide that the outer end of said outlet will extend well into the tray when the outlet is adjusted into discharging position, as shown by dotted lines in Fig. 2.

80 Referring now to Fig. 1 the reservoir is shown as extending for the full length of the switch rail and a plurality of trays 13 are employed and disposed between the several cross ties over which the switch rail extends. 85 The container or reservoir is provided with a number of outlets corresponding to the number of trays, so that when the container or reservoir is adjusted to the position shown by dotted lines in Fig. 2, the several trays 90 will be simultaneously supplied with inflammable liquid. In instances such as shown in Fig. 1, where two switch rails are used each tray may be sufficiently long to extend underneath the said switch rails as shown by 95 the construction of one of the trays in Fig. 1, which tray is indicated by *k*, or a greater number of shorter trays may be employed as is also shown in Fig. 1, in which instance, of course, there will be provided a reservoir *h* 100 for each series of trays. Or if further desired, a combination of short and long trays may be employed as is also shown in Fig. 1, the longer trays being employed at the portions of the switch rails which are connected 105 by the links *g* and the shorter trays under the other portions of the said switch rails.

When the device is not in use the reservoir as before stated is adjusted to the position shown in Fig. 2, and in order to prevent the turning of the outlets into discharging position suitable means such as set screws screwed through the yokes 9 and into binding engagement with the reservoirs or containers, are employed. When it is required to use the invention the set screws or other fastening means for the reservoir, or reservoirs as the case may be, are loosened after which the reservoir is turned to the position shown in Fig. 2. The inflammable 110 fluid is lighted in the trays upon flowing into these and the flame from such ignited fluid upon enveloping or partly enveloping the switch rails readily effects the melting of the ice or snow. It will be noted that the 115 volume of flow of the contents of the reservoir may be varied by turning the reservoir so as to adjust the outer end of the outlet to various distances above the tray so that the same action may be obtained as would 120 125 130

be had with a valve in the outlet. The use of valves with the outlets may be required in instances where it is desired to cut off the flow of liquid to any particular tray or 5 trays either by reason of the fact of the thawing having been more readily effected in the parts of the switch adjacent to those trays than in other parts, or by reason of the fact that certain parts of the switch 10 rail need not be thawed, or for any other reason. Therefore, it is to be understood that the right to use valves whenever found necessary, is reserved.

What is claimed as new is:

- 15 1. A thawing device for switch rails, comprising a tray arranged below the switch rail, and a reservoir or container for holding an inflammable substance and positioned at a point above the tray and having an outlet 20 arranged to direct the flow of inflammable fluid from the reservoir or container into the tray.
- 25 2. A thawing device for switch rails, comprising a tray arranged below the switch rail, and a reservoir or container for holding an inflammable substance and positioned at a point above the tray and having an outlet 30 adjustable to positions above the level of the liquid in the container or reservoir and below the said level and into alinement with the tray.
- 35 3. In a thawing device for switch rails, a horizontally disposed container or reservoir adjustably connected to the railway 40 track and having connected thereto an outlet or nozzle which is disposed so as to extend into the space between adjacent cross ties of the railway track when the container or reservoir is adjusted into one position.
4. In a thawing device for switch rails,

the combination of a horizontally disposed container or reservoir arranged so as to extend longitudinally of the railway track and adjustably secured to the same, and provided with an outlet or nozzle having a loop intermediate of its ends. 45

5. A thawing device for switch rails including a plurality of trays disposed in the road-bed and in the spaces between the cross ties and arranged so as to underlie the switch rail to be thawed, a horizontally disposed container or reservoir adjustably secured to the railway track and located above the trays and having a plurality of outlets or nozzles arranged so as to extend to points 55 in vertical alinement with the trays when the container or reservoir is adjusted into one position.

6. In combination with the oppositely disposed movable rails of a railway switch and the cross ties for supporting the rails; of a plurality of trays for holding a combustible liquid and arranged between adjacent cross ties, certain of said trays being relatively long and extending to points underneath the oppositely disposed switch rails, others of 60 said trays being relatively short and arranged in parallel series, one series, being disposed beneath one of said movable switch rails and the other series disposed beneath 65 the other of said movable switch rails.

In testimony whereof, we have signed our names to this specification in the presence of two subscribing witnesses, this 9th day of March, 1915.

FRANK A. HIGGINS.

THOMAS M. DUNNING.
